Patented May 3, 1960

187,811

CONDIMENT DISPENSER

Charles W. Heppenstall, Delray Beach, Fla.
Application June 10, 1958, Serial No. 51,291

Term of patent 14 years

(Cl. D44—22)

Fig. 1 is a perspective view of the condiment dispenser;
Fig. 2 is a side elevation view of the condiment dispenser;

Fig. 3 is a top plan view of the condiment dispenser;
and

Fig. 4 is a bottom plan view thereof.

I claim:

The ornamental design for a condiment dispenser, substantially as shown.
